COMBINATION SOAP DISH AND SOAP HOLDER

Maude F. Reed, Malden, Mass.

Application April 22, 1949, Serial No. 2,196

Term of patent 14 years

(Cl. D4—3)

To all whom it may concern:

Be it known that I, Maude F. Reed, a citizen of the United States of America, residing at Malden, in the county of Suffolk and State of Massachusetts, have invented a new, original, and ornamental Design for Combination Soap Dish and Soap Holder, of which the following is a specification, reference being had to the accompanying drawing, forming a part thereof.

In the drawing:

Figure 1 is a front elevational view, showing my new design of a combination soap dish and soap holder.

Figure 2 is a top plan view thereof; and

Figure 3 is a side elevational view.

I claim:

The ornamental design for a combination soap dish and soap holder, as shown.

MAUDE F. REED.
